UNITED STATES PATENT OFFICE.

GEORGE B. WADSWORTH, OF COVINGTON, KENTUCKY, ASSIGNOR TO THE WADSWORTH ELECTRIC AND MANUFACTURING COMPANY, OF COVINGTON, KENTUCKY, A CORPORATION OF KENTUCKY.

ELECTRIC SWITCH.

Application filed November 17, 1923. Serial No. 675,330.

My invention relates to externally operated switches and particularly to devices wherein the service door of the switch box carries a member which will expose the fuses within the box, but will not expose the live terminals therein. It relates further to a safety fuse construction whereby the service station can prevent the plugging of fuses required for domestic and factory protection without locking these normal fuses from access by the customer.

There are now a wide variety of patents on fuse renewal, externally operated boxes, some of which prevent access to the fuses until the switch is opened by an external handle, and some of which in addition to this provide a barrier within the box, preventing any tampering with the live terminals of the switch when the fuse are opened up for renewal or observation. My invention as noted, has as its object the provision of a switch box which carries in the lid a fuse exposing hopper-like structure, said hopper having a sliding shutter, operable by hand from outside of the box, but in which the switch operating member exercises an inhibition or interlock to prevent the sliding shutter from being operated when the switch is closed.

My invention also relates to the provision of a single block of insulating material such as slate or porcelain in which all terminals for wiring are at one end and still a customer's fuse or fuses are provided, as well as a service station fuse, which is removed from access through the fuse shutter.

I accomplish my objects by that certain construction and arrangement of parts to be hereinafter more specifically pointed out and claimed.

In the drawings:

Figure 1 is a front elevation of the inside of the box with the lid swung wide open.

Figure 2 is a rear plan view of the preferred form of switch and fuse block.

Figure 3 is a section on the line 3—3 of Fig. 1.

Figure 4 is a section on the line 4—4 of Fig. 1.

Figure 5 is a section on the line 5—5 of Fig. 1.

Figure 6 is a like section facing the opposite way of Figure 5 as by the line 6—6 of Fig. 1.

The box is preferably made of sheet metal having a base 1, sides 2, end 3, and hinged lid 4. The lid has flanges to engage over the box, and is held, or sealed shut by means of latch 5, pivoted on the face of the lid, engaging a slot in a tongue 6 on the side of the box, which tongue passes through a slot 7 in the lid, when the box is closed. The tongue and latch may also be sealed together through matching holes (not shown).

The switch operating device comprises a handle 8, having a hub 9, which is shouldered at 10, so that when thrust into place from the inside of the box, the hub will find a journal in a suitable hole in the box, and the shoulder will prevent withdrawal of the handle.

A yoke or bail 11, is provided, which engages as a pivot in a hole in one side of the box, and in a central hole in the hub 9 of the handle at the other side. The face of the hub is slotted so as to snugly engage the arm of the yoke or bail on its side, whereby the manipulation of the handle will rock the yoke.

There is pivoted on the side of the box away from the handle a plate 12, having a tongue 13 thereon which extends inwardly from the side of the box. This plate has also a cut 14 in the inner edge thereof, in which the transverse bar of the yoke rides, this cut terminating in two notches 15, so that when the yoke is rocked to come into the lower notch (Figure 5) it will pull down on the plate, lowering the position of the tongue 13. When the yoke is rocked upwardly the tongue 13 will be thrust upwardly toward the lid of the box.

The lid is formed with a hole 16 therein for fuse access. On the under side of this hole is formed a four sided casing or hopper 16 open at the inner end and opening into the hole, which hopper when the lid is closed comes down around the customer's fuses. Also, either of one piece with the hopper or as separate pieces along the side thereof are two plates 17, 17, which are raised away from the inner face of the lid, so as to form a guideway for a sliding shutter 18, which

guideway extends between the hopper and the lid, so that the shutter may close off the opening through the lid into the hopper.

Probably the best way of securing the 5 hopper and guide plates to the lid will be by spot welding, but it should be noted that it is not necessary that the shutter slide on the inside of the box, or that the hopper be confined solely to the inside of the box.

10 The shutter has a flange that is turned up along one edge thereof as at 19, and this flange will strike the tongue 13 on the plate 12, when the switch is moved by means of the yoke to open position. Also this flange 15 will prevent the swinging of the yoke to close switch position if the fuse shutter is open. This results from the relative positions of the tongue and shutter flange in each other's path, as will be evident from the 20 drawings.

The structure of the fuse and switch block I show in one piece with the terminals all on one end to facilitate wiring, but it will be understood from the point of view of 25 the fuse arrangement, that this is not essential, as the switch and fuse blocks might be separate conductors strapped or merely wired up between them.

I show but one switch bar 20, pivotally 30 secured to the terminal clip 21, and having a fork 22 of insulating material, which engages over the yoke, whereby the yoke will rock the switch bar. The switch bar closes connection between the terminal 21 and the 35 terminal 22^a. The terminals are all shown as mounted on a single block 23 of porcelain or slate, which has cups 24 for the two fuses 25, said cups being enclosed by the hopper on the door when the same is closed.

40 The rear of the block is strapped with a connection 26 from terminal 22^a to one of the terminals of the left hand fuse 25, the other terminal 25^a of this fuse either being exposed for connection to a wire lead or else 45 it can be strapped back to a terminal at the top of the block as shown in my application for patent, Serial No. 546,127, filed March 23, 1922.

The terminal 21 is strapped at 27 in the 50 back of the block to the terminal 28 of the service station fuse, which is in proximity to the switch blade, and hence out of access of the customer through the fuse hopper. The station fuse 29 set in a suitable cup 55 connects terminals 28 with one of the line terminals 30 of the switch. The other line terminal 31 of the switch is strapped through to the other customer's fuse 25, at 31^a and this fuse may again be strapped on 60 the back of the block to a terminal at the upper edge of the block, or may have its terminal 32 exposed, as in the drawings herein.

It may thus be noted, that the fuse 29 is 65 cut off access of the customer, and if one at-

tempts to plug the customer's fuses and overloads the circuit to which the current is delivered, the station fuse will burn out, thereby requiring the customer to call upon the service station inspector, who will then 70 discover that the customer has been abusing the switch installation. The fuse 29 will naturally be less sensitive than the fuses required by regulation to be used by the customer, and the use by the customer of 75 higher amperage fuses than he is supposed to use, will also result in detection by the service station, should the customer overload his circuit.

I have also shown a test switch generally 80 marked 33, located on the switch block for convenience in testing, and having tongues 34, 34, for clipping on the test wires.

It will be understood that I have described but one particular form of switch in 85 the above specification, and that I will set forth in my claims the invention which I believe to be inherent in structures of the nature now described by me.

Having thus described my invention, 90 what I claim as new and desire to secure by Letters Patent, is:—

1. In a switch box having a switch and fuses therein, a lid for the box having a fuse opening therein, a hopper mounted on the 95 lid about the fuse opening and adapted together with the lid, to house the fuses and to isolate them from the interior of the box, and a shutter controlling access to the fuse casing when the lid is closed.

2. In a switch box having a switch and fuses therein, a lid for the box having an opening therein in registry with the fuses in the box, exteriorly operable means for opening and closing the switch, a hopper carried by the lid and surrounding the opening therein, the hopper and lid being movable as a unit to a closed position wherein the fuse is housed within the hopper and isolated from the switch, said unit being movable to open the box and to provide unobstructed access to the entire interior of the box, and a shutter for the hopper adapted 105 when the lid is closed, to be locked and unlocked upon movement of the switch operating means in opening and closing the switch whereby the fuse is rendered accessible from the exterior of the box when the switch is open.

3. In a safety switch box structure the combination of a switch box, a perforate lid for the box, a hopper mounted on the inner face of the lid and surrounding the perforation therein, fuses in the box adapted to project into the hopper when the lid is closed for permitting access to the fuses from the exterior of the closed switch box and precluding access to the remainder of the interior of the box, and a controllable closure for the fuse hopper.

4. In a theft proof and safety switch box structure the combination of a switch box which when open affords free access to the entire interior of the box, a switch in the box, fuse connections disposed in the box at a distance from the switch, a perforate lid for the box, a continuous hopper structure open at opposite ends and secured to the lid about the perforation therein, and closing means for one of the open ends of the hopper structure, the hopper structure being adapted to receive the fuses through the remaining open end and to isolate them from the interior of the box when the lid is closed. 10

GEORGE B. WADSWORTH.
